UNITED STATES PATENT OFFICE.

CHARLES H. PHILLIPS, OF MALDEN, AND WILLIAM EMERY NICKERSON,
OF CAMBRIDGE, MASSACHUSETTS.

AUTOMATIC WEIGHING-MACHINE.

SPECIFICATION forming part of Letters Patent No. 554,029, dated February 4, 1896.

Application filed January 16, 1893. Serial No. 458,521. (No model.)

To all whom it may concern:

Be it known that we, CHARLES HENRY PHILLIPS, of Malden, and WILLIAM EMERY NICKERSON, of Cambridge, in the county of 5 Middlesex, State of Massachusetts, have invented certain new and useful Improvements in Automatic Weighing-Machines, of which the following, taken in connection with the accompanying drawings, is a specification.

10 Our invention relates to improvements in automatic weighing-machines, and has for its object the attainment of greater accuracy in automatic weighing than has heretofore been possible.

15 Our improved weighing-machine is adapted to act in connection with a continuous stream of material, and to either deliver the same in lots of uniform weight or by means of an ordinary registering device, simply to register 20 the total amount passed through it.

Our invention is illustrated in the accompanying drawings, in which—

Figure 1 shows the machine in front elevation but with a portion of the front framework removed in order that more of the working parts may be seen. Fig. 2 shows the details of construction of a part of the machine. Fig. 3 shows a knife edge of peculiar construction. Fig. 4 shows parts of the machine in a 30 different position. Fig. 5 shows the construction of the chute and deflector.

In the drawings, (see Fig. 1,) A represents the framework, within and upon which the working parts of the machine are mounted.

35 B and B' are two buckets or receptacles, into which the material to be weighed is delivered through the swinging chute C and pipe t from the bin T. The buckets are provided with standards b and b', upon which are mounted the links L and L', carrying the rollers l and l'. While the buckets are receiving their load these rollers l and l' rest upon the rollers r and r', which are mounted upon the lower extremities of the scale-beams R and R', upon 40 the outer ends of which are placed the weights W and W' respectively. The scale-beams R and R' rest upon the knife edges K and K' and are provided near their lower ends with the adjustable stops S and S', which limit the 45 movement of the scale-beams by bearing against the fixed parts s and s', and thus regu-

late the relative positions of the rollers r and r' to the rollers l and l'. At the upper ends of the standards b and b' are located the knife edges k and k', which bear upon the 55 balancing-beams E and E', which have their fulcrums at e and e', and carry upon their outer ends the weights w and w'. This arrangement serves to balance the weight of the buckets and to guide the standards b and b' 60 in their vertical movements. The buckets B and B' are provided with the discharge-doors D and D', hinged at their lower edges. The doors D and D' are provided with the arms d and d', which serve the purpose of closing 65 them upon the ascent of the buckets, after which they are secured in their closed position by the latches L² and L³.

F and F' are stops attached to the framework of the machine, and are so located as 70 to engage on the ascent of the buckets with the arms d and d', and thereby close the doors D and D'. The stops f and f' are likewise attached to the frame of the machine and serve by engaging with the latches L² and L³ 75 to open the doors D and D' upon the descent of the buckets.

The buckets B and B' are guided in their vertical movements by the arms G and G'.

The chute C (see Figs. 1 and 4) is connected 80 by the arm H, pivoted at h with the deflector c, which is pivoted at c' in such a manner that when the chute C swings to the right the deflector c moves to the left, whereby only half the movement of the chute C that would otherwise be required is necessary. The deflector c, which is pivoted at c', has a central portion c'', as shown by the dotted lines, which deflects the stream of material coming from the chute C into one bucket or the other, as 85 required. In the position shown in Fig. 1 the stream is being deflected into the bucket B'. The other parts of the deflector c consist merely of surrounding sides for preventing particles of material from being thrown out. 90 The chute C is operated by the bent levers M and M' fixed upon the shafts m and m'. The bent levers M and M' are provided at their lower ends with the springs I and I', which are attached to the fixed parts i and i'. Upon the same shafts with the arms M and M' are fixed the arms J² and J³, to whose 100

outer ends the rods J and J' are pivoted. These rods J and J' carry on their upper ends the rollers j and j' , which engage with the rollers N and N' upon the arms n and n' , and 5 serve to hold the bent levers M and M' in position against the tension of the springs I and I' , and as a trip arrangement by which the springs are allowed to operate and move the chute C at each descent of a weighing-
10 bucket. The arms J and J' bear against the rigid bars J^4 and J^5 , respectively, by which they are held in the proper position when in engagement with the arms n and n' . The arms n and n' are pivoted at O and O' , respectively. The arms n and n' tend by means 15 of the springs n^2 and n^3 , when not otherwise acted upon, to keep in contact with the eccentric limiting and adjusting rollers x and x' , respectively. It is not indispensable that 20 the arms n and n' and the rods J and J' have friction-rollers, as the result would be substantially the same if their ends were merely slightly rounded, but it is preferable in order to save friction that one or both should be so 25 provided. The arms n and n' , whose position, and consequently their stability with reference to the rollers N and N' , respectively, is regulated by the eccentric rollers x and x' , are further provided with the pieces Q and 30 Q' , which serve to throw the rollers N and N' past the vertical line of the rollers j and j' whenever the links L and L' trip upon their respective scale-beams. The eccentric rollers x and x' are firmly attached to rods extending from side to side of the frame of the 35 machine and regulate the position of the arms n and n' , respectively, and in relation to rollers j and j' by the rotation of the said rods.

P' (see Fig. 2) is a dash-pot mounted upon 40 the stem p' , fitting closely upon the piece R' , and is provided with the valved outlet V' and the adjustable vent v' . The vent v' consists preferably of a screw flattened on one side, the flattening being greatest at the point fitted into a threaded hole, whereby, by turning the screw in or out, the air is allowed to escape more or less rapidly, and the dash-pot thereby caused to retard the ascent of the bucket more or less, as occasion demands. 45 The stem p' (see Fig. 2) is supported by the arm U' when the bucket is in its loading position. The projection u' upon the standard b' serves upon the descent of the bucket to throw the arm U' out of engagement with the 50 stem p' , thereby allowing the dash-pot to descend and perform its function of retarding the return of the bucket to its upper position.

The adjusting-screws X and X' (see Fig. 1) serve to regulate the position of the rollers l 60 and l' , and thereby determine the sensitivity of the scale-beam trip device.

The knife edges K and K' of the scale-beams R and R' are prevented from moving laterally by a device shown enlarged and in perspective in Fig. 3. The prismatic piece k^2 projects into a recess in the knife edge, so that the contact is on the corners k^4 and k^5 of the

knife edge, which are exactly pivotal, thereby avoiding any friction in resisting the lateral movement of the beam. 70

Fig. 5 shows in vertical section the chute C and deflector c in the position in which they are discharging into the right-hand bucket, as shown by the arrow. The dotted lines show the position in which they would discharge into the left-hand bucket. 75

The operation of our machine is as follows: In Fig. 1 the bucket B is represented as discharging its load, the door D being opened and the bucket itself at the lower limit of its vertical movement. In the meantime the bucket B' is receiving its load through the chute C and deflector c , and depends by the intermediate mechanisms on the scale-beam R' , the door being closed. When the bucket B' 80 has received the amount of material for which the machine is adjusted—that is, enough to overcome the resistance of the weight W' —the end of the scale-beam R' which carries the roller r' is depressed, and being below the fulcrum K' it also has a lateral movement, which carries it to the right of the vertical line, or line of stability, of the rollers r' and l' , whereupon the latter flies out to the left and allows the bucket B' , with the attached standard b' , 85 to descend, taking down with it the inner ends of the balance-beam E' and raising the weight w' . During the descent of the bucket B' the latch L^3 engages with the stop f' and allows the door D' to open for the discharge of the 90 load. When the roller l' and the link L' are thrown to the left by passing the vertical line of stability, the link engages with the piece Q' , attached to the arm n' , carrying the roller N' , which is thereby also thrown to the left. This 95 carries the roller N' past the line of stability with reference to the roller j' , allowing the roller j' with the arm J' to rise through the action of the spring I' attached to the lower end of the bent lever M' , which, acting upon 100 the chute C , throws it to the left, the deflector c moving reciprocally to the right, which causes the stream of material to be shifted to the bucket B , which has in the meantime risen to its loading position by a series of 105 movements which will be explained farther on. During the descent of the bucket B' , after the link L' and the roller l' have moved to the left and performed their work, the projecting piece y' on the standard b' engages 110 with the lower end of the bent lever M , carrying it down and allowing the rollers N' and j' to again assume the positions shown in the drawings, and extending the spring I' , whereupon this part of the mechanism is upon the 115 next descent of the bucket B' again ready to perform its function of throwing the chute C , as above described.

The positions of the mechanisms for moving the chute C are shown in Fig. 4 at the moment when the bucket is in the act of descending but has not as yet reached the lower limit of its movement. The chute has been thrown over but the bucket has not descended far 120

enough for the projecting piece y on the standard b of the bucket to have engaged with the lower end of the bent lever M and by depressing it extend the spring I and reset the trip mechanism, consisting of the rod J , arm n , and rollers j and N . Further, when the bucket B' descends the arm u' on the standard b , (see Fig. 2,) coming in contact with the arm U' , throws it out of contact with the stem p' , allowing the latter to drop and thereby causing the dash-pot P' to assume its working position—*i. e.*, to drop over the piece R' —the inclosed air escaping through the valve V' .

The movement by which the bucket B , after having discharged its load, returns to its upper or loading position will now be described. The weight w , through the balance-beam E , being somewhat heavier than the empty bucket B and its attached parts, causes it to ascend. The bucket B , however, does not ascend with an unrestricted movement, but is retarded sufficiently to allow the complete discharge of its load and to prevent the last portions of material from being shut in by the too sudden closing of the door D , by the action of the dash-pot mechanism heretofore described, which allows it to rise only as fast as the air can gain access through the adjustable vent. When the dash-pot drops, the inclosed air escapes through its upwardly-opening valve.

On the first ascent of the bucket it rises a little higher than its loading position proper, on account of the counterweight w being the heavier. This serves several purposes. It allows the roller l to swing over the roller r , it causes the arm d to raise the door D high enough to be secured by the latch L^2 , and it carries the stem p high enough for the end of the arm U to drop under the shoulder near the lower end of the stem. The bucket B has risen before the next descent of the bucket B' , and consequently is ready to receive its load when the chute C is again thrown over by the said descent of the latter bucket. As soon as enough of the load has run into the bucket B to make it heavier than the counterweight w , it drops until the roller l is seated upon the roller r . This frees the top of the standard b from contact with the stem p , the latter being held up by the arm U , and it also causes the arm d to drop out of contact with the stop F . The bucket B is now in its normal leading position and rests on the roller r and knife edge k , and is free from all other contacts except those of the guiding-arms G and G' , and is consequently very sensitive to the slightest variation of its load.

While the bucket B is loading the bucket B' is discharging its load and returning to its loading position.

In this manner the machine is adapted to weigh a continuous stream of material which may be divided into lots of uniform weight by receiving each discharge of the buckets in a separate receptacle, or to simply register the amount passed through the machine by

attaching any well-known registering device to register the number of discharges of the buckets, allowing all the material to run into a common conveyer.

The gist of our invention consists chiefly, first, in mechanism involving a spring which is set through the weight of material being weighed and is released when a full load is reached, whereby the chute is quickly shifted; second, in the mechanism by which the lateral movement of the scale-beams on their knife edges is checked without undue friction; third, in a dash-pot mechanism which is not in contact with the buckets or their standards while the buckets are supported by the scale-beam; fourth, in a scale-beam and bucket connected by a suitable trip device, operating in connection with a balance-beam which returns the empty bucket and guides it with little friction; fifth, in mechanism involving the scale-beam trip device and an adjusting-screw located independently of the bucket-standard, and in a stop for the scale-beam which is located near the trip-roll of the beam, whereby constancy of adjustment is secured.

We claim—

1. In a weighing-machine, the combination of the chute C and bucket B ; with the spring I , arm M , said arm M having a suitable locking device for sustaining the tension of the spring I , until unlocked by a movement consequent upon the weighing-bucket having received the desired weight of material, substantially as and for the purpose set forth.

2. In a weighing-machine, the combination of the bucket B , chute C , arm M , spring I , and rod J ; with the arm n adapted to pass the line of stability with reference to the rod J , when the weighing-bucket has received its proper load, substantially as and for the purpose set forth.

3. In a weighing-machine, the combination of the chute C , arm M , spring I , rod J , and arm n ; with the link L which by flying out when the desired weight is reached carries the arm n past the line of stability with reference to the rod J allowing the spring I to throw the chute C , substantially as and for the purpose set forth.

4. In a weighing-machine, the combination of the chute C , arm M , and spring I , said arm M being provided with a locking device; with the projection y on the standard b whereby the spring I is extended by the descent of the loaded bucket and held by the locking device, substantially as and for the purpose set forth.

5. In a weighing-machine, the combination of the knife edge K and its bearing; with the prismatic projection k^2 which by contact with the pivotal corners of the knife edge K prevents lateral motion without friction, substantially as and for the purpose set forth.

6. In a weighing-machine, the combination of the bucket B' and standard b' , the limit of whose vertical movement is slightly above its position when loading; with the stem p' ,

- dash-pot mechanism, arm U' adapted to sustain the stem p' and arm u' on the standard b' , whereby the stem p' is held out of contact with the standard b' when the bucket is loading and is allowed to descend when the load is discharged, for the purpose of regulating the ascent of the bucket to its loading position, substantially as and for the purpose set forth.
- 10 7. In a weighing-machine, the combination of the bucket B , weighing-beam R , standard b , and a suitable trip device operating between the said beam R and said standard; with the balance-beam E connected with said standard b and having the knife edge e , and the weight w , said weight being sufficient to overbalance the bucket B , and return it when empty to its loading position, the beam E guiding the standard b in its vertical movements without sliding friction, substantially as and for the purpose set forth.

8. In a weighing-machine, the combination of the roller r upon the scale-beam R with the roller l , link L and adjusting-screw X , said screw being mounted upon a part of the fixed framework of the machine, substantially as and for the purpose set forth. 25

9. In a weighing-machine, the combination of the scale-beam R , roller r , link L and roller l ; with the adjusting-screw X , located in the scale-beam R , near the roller r and the fixed piece s which engages with the screw, substantially as and for the purpose set forth. 30

In testimony whereof we have signed our names to this specification, in the presence of 35 two subscribing witnesses, on this 18th day of October, A. D. 1892.
